P. SCHULTZ

SLIDE TROLLEY

Filed April 17, 1922

Fig. 1.

Inventor:
PAUL SCHULTZ

By Earl M. Sinclair
Atty.

UNITED STATES PATENT OFFICE.

PAUL SCHULTZ, OF DES MOINES, IOWA.

SLIDE TROLLEY.

Application filed April 17, 1922. Serial No. 553,686.

To all whom it may concern:

Be it known that I, PAUL SCHULTZ, a citizen of the United States of America, and resident of Des Moines, Polk County, Iowa, ⁵ have invented a new and useful Slide Trolley, of which the following is a specification.

The object of this invention is to provide an improved trolley device of the sliding type.

¹⁰ A further object of this invention is to provide an improved trolley slide shoe which may be reversed, whereby the life of the device is materially increased.

¹⁵ A further object of this invention is to provide an improved reversible trolley slide shoe adapted to remain normally in one position during forward movement of the vehicle on which it is used and to reverse automatically upon and during reverse movement of such vehicle, together with means to limit rotary movement of the shoe.

²⁰ A further object of this invention is to provide an improved double stop member adapted to limit rotary movement of a slide shoe to substantially one-half a revolution, so that said shoe may assume either of two positions indicated for forward or reverse movement of the vehicle on which it is used.

My invention consists in the construction, ²⁵ arrangement and combination of elements hereinafter set forth, pointed out in my claims and illustrated by the accompanying drawing, in which—

³⁰ Figure 1 is a side elevation illustrating my improved slide trolley, dotted lines indicating the position assumed by the shoe for reverse movement, rotary movement of the shoe being limited to a range between the two positions so shown. Figure 2 is a section on the line 2—2 of Figure 1, and Figure 3 is a section on the line 3—3 of Figure 1.

³⁵ In the construction of the device as shown the numeral 10 designates the socket of a harp formed with spaced arms 11, 12, the socket being mounted on a pole 13, carried in turn by a trolley car or electric locomotive, not shown. A spindle 14 is mounted through and carried by the harp arms 11, ⁴⁰ 12 and a shoe 15, is mounted for oscillation on said spindle between said arms. The shoe 15 is of elongated form and has a hub 16 between its ends but located nearer the rear than the forward end, the forward portion of said shoe being formed with a rela-

tively large aperture 17, of greater width than the diameter of said hub, lying wholly between the front end of the shoe and the hub 16. The shoe 15 is formed with a groove 18 adapted to engage a trolley wire ⁶⁰ (not shown), such groove extending around three sides of the shoe, that is to say the top, rear and bottom sides. The groove 18 at the top and bottom of the shoe is straight for a distance for extended contact with a wire, such straight portions being connected by an arcuate portion at the rear of the shoe. The grooved top portion of the shoe is adapted for contact with a wire during normal forward travel of the device, and in the event the direction of travel is reversed said shoe automatically turns about a half revolution in the direction indicated by the arrow in Figure 1, whereby the grooved lower (as shown) portion thereof contacts with the wire, said wire contacting with the arcuate rear portion of the shoe during such movement of reversal. In other words, that portion of the shoe having the large aperture 17 is always in advance of the spindle ⁷⁰ 14, regardless of the direction of travel of the vehicle. When the shoe has been in use for a time and its normal top portion becomes badly worn, it may be reversed by removing it from the spindle and turning it ⁷⁵ top for bottom so that the portion formerly used in rearward travel only is thereafter used in forward travel; thus materially lengthening the effective life of the shoe.

⁸⁰ There is sometimes a tendency of the shoe to turn more than the half revolution required for its automatic reversal from the forward to rearward movement position above explained, as for instance when it encounters an obstruction on the trolley wire ⁸⁵ such as an overhead circuit breaker or a switch joint, and such excessive turning is liable to result in displacement of the shoe from the wire. To prevent this I have provided a double-stop device, composed of a ⁹⁰ tubular member or nut 19 mounted on and embracing one end portion of the hub 16 of the shoe. The tubular member or nut 19 is formed at its outer end with an integral extension or lug 20 substantially parallel ⁹⁵ with its axis and overlying and engaging the upper end of one of the harp arms, such as 11, whereby said tubular member or nut is prevented from turning and is held stationary relative to the harp. At its inner ¹⁰⁰ 110

end the tubular member or nut is formed with circumferentially spaced stop shoulders 21, 22, which are spaced apart substantially 180 degrees on the circumference 5 of the member, or a trifle more. The shoulder 21 is adapted to be engaged by a lug 23 formed on one side of the shoe 15, to limit rotation of said shoe in a direction opposite to the arrow in Figure 1; and the shoulder 22 10 is adapted to be engaged by the opposite side of said lug at times to limit rotation of said shoe in the direction indicated by said arrow. In other words said shoulders, by engagement with the lug 23, permit only 15 such rotation of the shoe as to allow it to pass from its normal position for forward travel, as shown by solid lines in Figure 1, to its position for rearward travel, as indicated by dotted lines in said figure, and 20 vice versa, or about 180 degrees in either direction.

In order to provide stop means for engagement with the shoulders 21, 22 when the shoe has been reversed by turning top 25 for bottom, as hereinbefore noted, a second lug 24 is formed on the opposite face thereof from the lug 23, said lug 24 being suitably spaced circumferentially from the lug 23 that it will occupy the proper position relative to said shoulders when such reversal is made. That is, the lug 24 is as far below the longitudinal axis of the shoe as the lug 23 is above it.

The device may, if desired, be equipped 30 with the usual trolley wheel springs, such

as 25, one of which is shown in this instance.

I claim as my invention—

1. A slide trolley, comprising a harp, an elongated slide shoe mounted for oscillation therein, said shoe being adapted to contact a wire on either of its long sides, and means to limit oscillation of said shoe. 40

2. A slide trolley, comprising a harp, a shoe mounted for oscillation therein, and means for limiting oscillation of said shoe to substantially a half revolution in either direction. 45

3. A slide trolley, comprising a harp, a slide shoe mounted for oscillation therein, a stop member rigidly mounted and formed with a pair of spaced stop shoulders, and a lug formed on said shoe and adapted for engagement with said shoulders to limit oscillation of said shoe in either direction. 50

4. A slide trolley, comprising a harp, a spindle carried thereby, a slide shoe formed with a hub journaled on said spindle, and a tubular stop member mounted on said hub, said stop member being formed with an extension engaging said harp to prevent rotation of said stop member, said stop member being formed with spaced stop shoulders, said shoe being formed with a lug adapted for engagement with said shoulders selectively. 60

Signed at Des Moines, in the county of Polk and State of Iowa, this 12th day of April, 1922.

PAUL SCHULTZ.
